UNITED STATES PATENT OFFICE.

MICHAEL J. FLAVIN, OF GREENFIELD, MASSACHUSETTS, ASSIGNOR TO WILLIAM BARRY, OF ORANGE, MASSACHUSETTS.

GRINDING, POLISHING, AND BUFFING MACHINE.

1,193,886.

Specification of Letters Patent.

Patented Aug. 8, 1916.

Application filed September 18, 1915. Serial No. 51,373.

To all whom it may concern:

Be it known that I, MICHAEL J. FLAVIN, a citizen of the United States of America, and resident of Greenfield, in the county of 5 Franklin and State of Massachusetts, have invented certain new and useful Improvements in Grinding, Polishing, and Buffing Machines, of which the following is a full, clear, and exact description.

- 10 This invention relates to a machine primarily designed for the polishing of cross sectionally circular articles and more especially those having bulging or convex, concave, or ogee contours.
- 15 The object of the invention is to provide a machine in which the article to be polished is mounted on the upper end of a spindle having means for the rapid rotation thereof and in which a head carrying a polishing 20 wheel or wheels is capable of movements both in a downward direction to bring the polishing element into the region of the mounted piece to be polished and transversely movable for presenting the polishing 25 element against all portions of the curved side of the piece.

The invention is described in conjunction with the accompanying drawings and is set forth in the claims.

- 30 In the drawings:—Figure 1 is a plan view; Fig. 2 is a side elevation of the improved polishing machine. Figs. 3 and 4 are respectively a partial rear elevation and partial side elevation of the machine showing 35 a modification in the manner of mounting the frame by which the polishing wheel spindle is carried. Figs. 5 and 6 are elevations at right angles to each other showing arrangements whereby the usual upright 40 work carrying spindle may be revolvably adjusted whereby the work may be held in the most advantageous position for receiving the action of the polishing wheel thereon. Figs. 7 and 8 are sectional views as taken on line 45 7—7, Fig. 2, showing the clutch device for connecting the work carrying spindle with the pulley for the driving thereof,—one thereof showing the parts in clutch and the other showing the parts out of clutch.

- 50 Fig. 9 is a horizontal cross sectional view as taken on line 9—9, Fig. 6, for showing a detail of construction hereinafter referred to.

In the drawings, A represents the frame of the machine at the rear end of which is 55 mounted a horizontal transverse driving

shaft B having a driving pulley C whereby through belt D the shaft is driven.

At the forward end of the frame is a substantially upright work carrying spindle E which is rotatable in and through the frame 60 A and is capable of an endwise sliding movement within a slight range vertically through bracket-like members of the frame.

The upper and lower ends of the spindle are respectively above and below the frame 65 members as shown in Figs. 2 and 7 and 8. The work is carried directly or through any equipment therefor at the upper projecting end of the spindle. The spindle has loosely thereabout the pulley F which rests on the 70 lower bracket member a of the frame. The spindle between the lower bracket member a and the upper bracket member a^2 of the frame has affixed thereon a downwardly convergent clutch member b ; and the loose 75 pulley F is formed with an upwardly open, downwardly convergent, clutch socket d ,—these adjacent parts so coacting that when the spindle is permitted to descend gravitatively under its own weight and the additional weight of the conical clutch member b , it will become engaged with the pulley and be rapidly rotated by the latter through the driving connection therewith of the crossed 80 belt f driven from the pulley g on the driving shaft B of the machine.

G represents a treadle motion consisting of the pedal member h , the intermediately pivoted lever h^2 , and the connecting link h^3 . The forward end of the intermediately pivoted lever comprised in the treadle motion lies closely under the lower end of the spindle, and normally disengaged from, or ineffective relatively to, the spindle whereby the latter may normally gravitatively and 90 automatically be in clutch with its driving pulley F. The treadle is operated to disconnect the spindle from the driving means therefor when the work is to be mounted on or removed from the spindle.

Referring to Figs. 1 and 2, H represents a frame mounted for a vertical swinging movement on and relatively to the driving shaft, such frame extending forwardly from the shaft to the front end of machine, and such frame is also capable of a movement horizontally and transversely relatively to its spindle in addition to its capability of transverse horizontal movement. The frame as shown comprises, or is employed in con- 105 110

junction with, a yoke J which is mounted tiltably or for a partial revoluble movement on the main shaft B. The rear portions of the members of the frame H are 5 connected by trunnion joints i, centrally to the upper and lower portions of the yoke J whereby the frame has the aforementioned capability of transversely and horizontally swinging on the substantially vertical pivot 10 axes i i. The frame H is formed at its forward end with a head K in which is mounted a substantially transverse shaft L, intermediately carrying a pulley L² and having at its extremity, which is adjacent 15 and above the work carrying spindle E, one or more polishing wheels k k².

Wheels of different sizes and character are to be interchangeably employed on the polishing wheel shaft L. In Figs. 1 and 2, 20 two wheels are shown, the one k being of a larger diameter than the one k²,—one of these wheels being of a coarse abrading character while the other is to be finer and for the finishing of the work.

25 m represents a portion of a cord or chain understood as running over an elevated sheave and having counterpoise weight (not shown) and as common in swinging tool carrying heads or frames.

30 The polishing wheel shaft pulley L² is driven from the main shaft pulley M by the belt N.

o represents a handle rigidly connected to the polishing wheel shaft carrying head, 35 and to be made use of manually for bringing the polishing wheel down to proximity to the piece to be polished and by transverse movement against the side of the piece.

By employing a cross belt for driving the 40 spindle E, the work and polishing wheel have relatively opposite rotations, which manifestly result in an acceleration of the polishing action.

In the utilization of the machine, the operative 45 first presses the pedal member of the treadle motion, causing a cessation of the rotation of the work carrying spindle, and then mounts the work on the upper end of such spindle, whereupon he releases the 50 treadle permitting the spindle to become clutched and rapidly rotated; he then, through the handle o downwardly swings the frame to bring the polishing wheel onto the surface of the usually non-cylindrical 55 piece to be polished and moves the frame transversely as required to maintain the polishing wheel in its working contact on the bulging or hollowing surface of the piece, maintaining the wheel in its working 60 position until the part has been finished.

In Figs. 5 and 6 the portion of the frame A in and through which the work carrying spindle E is substantially vertically mounted, is formed as a head P mounted on a 65 bracket-like portion A² of the frame proper

for a tilting or partially revoluble adjustment on a horizontal pivot axis which is longitudinally of the machine and whereby the spindle and its work may be tilted to proper inclination in a plane crosswise of 70 the machine, so that round pieces of work of certain peculiar shapes may be so held while being rotated as to better permit the operative access thereagainst of the polishing wheel or wheels.

In Fig. 6 the revoluble adjustable head P is indicated as having a stud P² which passes through and beyond a hole therefor in the bracket portion A² of the frame and receives the nut t for the confinement of the 75 head in its proper adjustment.

When the machines are equipped with the revolubly adjustable head P so that at times the work carrying spindle E is swung considerably from the vertical line, an intervening thrust rod u is provided for an up and down, but non-rotative movement through a suitable part of the frame, such thrust rod having an arc-shaped extension u² which has a curvature corresponding to the path 80 of movement of the end of the revolubly adjustable spindle; and therefore, irrespec- 85 tive of the degree of inclination of the spindle (within reasonable limits) the treadle motion will always be effective for 90 its proper coaction with the spindle.

In Figs. 3 and 4 the frame H which carries the polishing wheel head at its forward end instead of being pivotally jointed to the yoke J, whereby it may swing horizontally relatively to the tilttable yoke, is indicated as rigidly connected to the yoke, but the yoke is slidale along the transverse main shaft B so that through the sliding as well as the tilting motions of the 105 yoke, substantially the same movements may be imparted to the polishing wheel head as have been already described.

The wheels to be employed in this machine while most times are polishing wheels may 110 at election of the user, be grinding wheels or buffing wheels.

I claim:—

1. In a polishing machine, in combination, an upright spindle for carrying the 115 work at its upper end, and means for rotating the spindle, a head, carrying a horizontal polishing wheel, above the work spindle, pivotally mounted and free for a swinging movement in a vertical plane down into proximity to and upwardly away from the spindle, and also freely movable transversely relatively to the axis of the spindle, and means for rotating the grinding wheel.

2. In a polishing machine, in combination, an upright work-carrying spindle having a clutch member thereon, a pulley through which the spindle is substantially vertically movable, formed with a clutch member, a treadle coacting with the spindle 125 130

for vertically moving the latter for effecting the clutching and unclutching of the spindle and pulley, a head carrying an axially horizontal polishing wheel above the work spindle pivotally mounted for a vertical swinging movement down toward and upwardly away from the spindle, and also movable transversely relatively to the spindle, means for rotating said pulley, and means for rotating the grinding wheel.

3. In a polishing machine, in combination, a substantially upright spindle for carrying the work at the upper end thereof, a head,—in which such work carrying spindle is rotatively carried,—mounted for revoluble adjustment on a horizontal axis, and means for rotating the spindle, a head, carrying a horizontal polishing wheel, above the work spindle, pivotally mounted and free for a swinging movement in a vertical plane down into proximity to and upwardly away from the spindle, and also freely movable transversely relatively to the spindle, and means for rotating the grinding wheel.

25 4. In a polishing machine, in combination, an upright work-carrying spindle having a downwardly convergent clutch member thereon, a pulley through which the spindle is substantially vertically movable, formed with an upwardly open, downwardly convergent clutch socket and below which pulley the spindle extends, a treadle coacting with the lower end of the spindle, and operable to vertically move the latter to lift the 30 conical clutch member from, and to permit it to fall to engagement in the conical socket in said pulley, a head carrying a horizontal polishing wheel above the work spindle pivotally mounted for a vertical swinging movement down toward and upwardly away from the spindle, and also movable transversely relatively to the spindle, means for rotating said pulley, and means for rotating the grinding wheel.

45 5. In a polishing machine, in combination, a supporting frame, a horizontal driving shaft mounted in the rear portion of said frame, an upright spindle, for carrying the work at the upper end thereof, mounted in a forward portion of said frame and provided with a pulley, a pulley on said driving shaft and a belt connecting such pulley and the spindle pulley, a frame mounted for a vertical swinging movement on said driving shaft, extended forwardly therefrom, such frame being also capable of a movement horizontally and transversely of the said spindle, and provided at its forward extremity with a head above the spindle, a 50 horizontal shaft in said head provided with a polishing wheel, pulleys on the driving shaft and the polishing wheel shaft, and a belt around said pulleys.

60 6. In a polishing machine, in combination, a supporting frame, a horizontal driv-

ing shaft mounted in the rear portion of said frame, an upright spindle for carrying the work at the upper end thereof mounted in a forward portion of said frame and provided with a pulley, a pulley on said driving shaft and a belt connecting such pulley and the spindle pulley, a yoke embracing and revolubly movable relatively to the driving shaft, a frame pivotally connected on a vertical axis to said yoke for 70 a horizontal swinging movement transversely relatively to the work carrying spindle, extended forwardly from the yoke and provided at its forward extremity with a head above the work carrying spindle, a 75 horizontal shaft in said head provided with a polishing wheel, pulleys on the driving shaft and the polishing wheel shaft and a belt around said pulleys.

7. In a polishing machine, in combination, 80 a supporting frame, a horizontal driving shaft mounted in the rear portion of said frame, a work spindle carrying head mounted for a revoluble adjustment on a horizontal axis at the forward part of the frame, a 85 substantially upright work carrying spindle rotatively mounted in said head and provided with a clutch member, a pulley loose on said spindle and through and below which the spindle extends, formed with a clutch 90 member with which the clutch member of the spindle coacts, a treadle coacting with the spindle for vertically moving the latter for effecting the clutching and unclutching of the spindle and pulley, a pulley on the 95 driving shaft and a belt connecting such pulley and the spindle pulley, a frame mounted for vertical swinging movement on such shaft extending forwardly therefrom and provided at its forward extremity 100 with a head above the work carrying spindle and such head-provided frame being also capable of a movement horizontally and transversely of the spindle, a horizontal shaft in said head provided with a polishing 105 wheel, pulleys on the driving shaft and the polishing wheel shaft, and a belt around said pulleys.

8. In a polishing machine, in combination, 110 a supporting frame, a horizontal driving shaft mounted in the rear portion of said frame, a work spindle carrying head mounted for a revoluble adjustment on a horizontal axis at the forward part of the frame, a substantially upright work carrying spindle 115 rotatively mounted in said head and provided with a clutch member, a pulley loose on said spindle and through and below which the spindle extends, formed with a clutch member with which the clutch member of the spindle coacts, a treadle motion, 120 a vertical thrust rod vertically, but non-rotatively, guided in the frame, with the lower end of which a member of the treadle motion coacts and the upper end of which is 125 130

located adjacent the lower end of the spindle and is provided with a transversely extended arc formed extension having a curvature corresponding to the path of movement of the end of the revolubly adjustable spindle, and adapted to coact with the spindle for vertically moving the latter for effecting the clutching and unclutching of the spindle and pulley, a pulley on the driving shaft and 10 a belt connecting such pulley and the spindle pulley, a frame mounted for vertical swinging movement on such shaft extending forwardly therefrom and provided at its forward extremity with a head above the work 15 carrying spindle and such head-provided frame being also capable of a movement horizontally and transversely of the spindle, a horizontal shaft in said head provided with a polishing wheel, pulleys on the driving 20 shaft and the polishing wheel shaft, and a belt around said pulleys.

Copies of this patent may be obtained for five cents each, by addressing the "Commissioner of Patents, Washington, D. C."

9. In a polishing machine, in combination, a work carrying spindle having a clutch member thereon, another clutch member co-acting with the first clutch member and 25 means for rotating it, and means for throwing the one clutch member into and out of engagement with the other, and a head, carrying an axially horizontal polishing wheel, above the work carrying spindle, 30 pivotally mounted and free for a swinging movement in a vertical plane down into proximity to and upwardly away from the work carrying spindle, and also freely movable horizontally relatively to the work 35 carrying spindle.

Signed by me at Springfield, Mass., in presence of the subscribing witness.

MICHAEL J. FLAVIN.
